UNITED STATES PATENT OFFICE.

JOSEPH B. STRAUSS, OF CHICAGO, ILLINOIS.

BASCULE BRIDGE.

Application filed February 17, 1921, Serial No. 445,604.

To all whom it may concern:

Be it known that I, JOSEPH B. STRAUSS, a citizen of the United States, residing at Chicago, in the county of Cook and State 5 of Illinois, have invented a certain new and useful Improvement in Bascule Bridges, of which the following is a specification.

This invention relates to improvements in bascule bridges and has for its object to 10 provide a new and improved device of this description. The invention has among other objects to provide a suitable support for the main span which will give ample space for a large volume counterweight of 15 cheap material such as concrete, and which will reduce the cost of constructing bridges of this type. The invention is illustrated in the accompanying drawings wherein

Fig. 1 is a side view showing one form of 20 bridge embodying the invention;

Fig. 2 is a plan view with parts omitted showing the construction illustrated in Fig. 1;

Fig. 3 is a sectional view on line 3—3 of 25 Fig. 2 showing the bearing 4^a for one of the inside trunnions;

Like numerals refer to like parts throughout the several figures.

In carrying out my present invention I 30 provide a bascule bridge having a main span 1, having the main trusses 2, one at each side of the main span. These main trusses are provided with trunnions 3. The 35 outside trunnions are mounted in bearings 4, and the inside trunnions in bearings 4^a, said bearings being carried by suitable supporting means. In the construction illustrated I provide a truss frame 5 on the outside of each main truss of the main span.

40 This truss frame comprises two members 6 and 7 inclined with relation to each other and connected together at the bottom by the member 8. A cross member 9 is connected with the two members 7 on opposite 45 sides of the main span and extends beneath it. It will be noted that these members 7 are inclined in a forward direction from the trunnions, that is toward the forward end of the main span and away from the tail or rear end. It will further be noted that 50 the cross member 9 is inclined in a similar manner. The outside trunnion bearings of the main span are mounted upon the members 6 and 7. Each outside supporting frame is provided with an inclined member 10. These members 10 connect with the

associated members 11 of each frame. Cross pieces 12 connect the members 7 and the members 10 and 11. The members 11 project up above the lower ends of the members 10 and act as supports for the main span at a point ahead of the trunnions. There is a second cross member 13 which connects with the opposite members 10 and which extends beneath the main span. The 60 inside trunnion bearings 4^a are supported on the cross members 9 and 13. It will thus be seen that there is no cross member which runs vertically beneath the trunnions, but that the cross member or members by which the inside trunnions are supported are inclined in a forward direction so that their 65 center lines are on the forward side of the vertical line through the axis of the trunnions. It will also be seen that the center 70 lines of these two inclined cross members intersect in the trunnions and that the lines from the centers of the trunnions through the center of these cross members runs along the axis of the inclined members 7 and 10, 75 and when these cross members are girders this line runs along the webs of the girders.

The main span is provided with a counterweight 15 which preferably extends 80 across the main span between the main 85 trusses 2. This counterweight is preferably made of large bulk, low cost material, such as concrete or the like.

It will be seen that with this construction 90 there is no vertical supporting member beneath either the outer or inner trunnions, and that the cross member 9 nearest the counterweight is at one side of the vertical line through the center of the trunnions and is inclined in a forward direction so that 95 its lower edge is a considerable distance from this vertical line. It will thus be seen that this gives a large amount of space for the counterweight as there is nothing to interfere with the movement of the counterweight when the bridge is opened, and thus 100 gives a large angle of opening, a portion of the counterweight being free to pass beyond this vertical line through the center of the trunnions without interfering with any of 105 the trunnion supporting structures. In other words this construction leaves a clear room for this large counterweight so as to permit this large angle of opening of the 110 main span.

It will further be seen that the reactions of the trunnions are transmitted to the out-

side supporting frame 5, the reactions of the inside trunnions being transmitted to the members of said frame through the cross members 9 and 13. The frames on the outside of the main trusses it will be noted have inclined members which form a stiff resisting frame for the stresses, and it will further be seen that the direction of transmission of these stresses runs centrally of the members of this frame. The upper ends of the members of the frame 5 are preferably connected together by suitable plates or the like 16 at the top, and by suitable members or the like 17 and 18 at the bottom. In Fig. 3 I have shown one form of the inside trunnion bearing. This construction saves material, prevents obstruction to the large bulk low cost counterweight, gives sufficient space for it, and at the same time permits the large angle of opening required.

I have described in detail a particular construction embodying the invention but it is of course evident that the parts may be varied without departing from the spirit of the invention as embodied in the claims here-to attached, and I therefore do not limit myself to the particular construction shown.

I claim:

1. A bascule bridge comprising a main span having main truss members one on each side thereof, outside and inside trunnions connected with said truss members, bearings for said trunnions, an outside frame on each side of the main span having inclined members connected together to form a stiff frame, some of said members being inclined toward the forward end of the main span, the bearings for the outside trunnions being mounted upon said frames, cross members connecting the members of the frame on opposite sides of the main span which incline forwardly, the inner trunnion bearings being mounted upon said cross members.

2. A bascule bridge comprising a main span, main trusses on opposite sides of said main span, said trusses having inside and outside trunnions connected therewith, bearings for said trunnions, a supporting frame on the outside of each main truss upon which the bearings of the outside trunnions are supported, said supporting frames having forwardly inclined members, a cross member connecting two of the forwardly inclined members of said frame, said cross support being also forwardly inclined, the inside trunnion supports of the trunnions being connected with said cross support, and means for transmitting the stresses from said cross support to said outside frame.

3. A bascule bridge comprising a main span, main trusses on opposite sides of said main span, said trusses having inside and outside trunnions connected therewith, bearings for said trunnions, a supporting frame on the outside of each main truss upon

which the bearings of the outside trunnions are supported having two forwardly inclined members, two cross supports connecting the forwardly inclined members on opposite sides of the main span, the bearings for the inside trunnions being mounted upon said cross members.

4. A bascule bridge comprising a main span, a large bulk, counterweight connected with the rear end of said main span, inside and outside trunnions for said main span, bearings for said trunnions, two frames on opposite sides of the main span, a cross member located in a plane at an angle to the vertical plane extending through the center of the trunnions and connected with said frames the bearings for the inner trunnions being connected with said cross member whereby increased space for said large bulk counterweight is secured.

5. A bascule bridge comprising a main span, a large bulk, counterweight connected with the rear end of said main span, inside and outside trunnions for said main span, bearings for said trunnions, two frames on opposite sides of the main span, two cross members located in planes at an angle to the vertical plane extending through the center of the trunnions and connected with said frames, one cross member being forward of the other, bearings for the inside trunnions mounted upon said cross members, whereby increased space for said large bulk counterweight is secured.

6. A bascule bridge comprising a main span, outside and inside trunnions therefor, bearings for said trunnions, two stiff frames, one on each side of the main span, said frames made up of two members inclined at an angle to each other, one of said members forward of the vertical plane extending through the trunnions, a cross member connecting the latter members on opposite sides of the main span, the inside trunnion bearings being connected with said cross member.

7. A bascule bridge comprising a main span, outside and inside trunnions therefor, bearings for said trunnions, two stiff frames one on each side of the main span, said frames made up of two members inclined at an angle to each other, one of said members forward of the vertical plane extending through the trunnions, a cross member connecting the latter members on opposite sides of the main span, the inside trunnion bearings being connected with said cross member, a third inclined member connected with each of said frames, a cross member connecting the said third member on opposite sides of the main span, the inside trunnion bearings being also connected with said latter cross member.

8. A bascule bridge comprising a main span, outside and inside trunnions therefor,

bearings for said trunnions, two stiff frames one on each side of the main span, said frames made up of two members inclined at an angle to each other, one of said members 5 forward of the vertical plane extending through the trunnions, a cross member connecting the latter members on opposite sides of the main span, the inside trunnion bearings being connected with said cross member, a third inclined member connected with each of said frames, a cross member connecting the said third member on opposite

sides of the main span, the inside trunnion bearings being also connected with said latter cross member, a vertical member connected with the other members of each of said frames, said vertical member adapted to be engaged by a portion of the main span in front of the trunnions when the main span is closed. 15

Signed at Chicago, county of Cook, and State of Illinois, this 5th day of February, 1921.

JOSEPH B. STRAUSS.
